UNITED STATES PATENT OFFICE.

HENNING FRIEDRICH WALLMANN, OF CHICAGO, ILLINOIS.

APPARATUS FOR DISTILLING FUEL.

1,210,388.

Specification of Letters Patent. Patented Dec. 26, 1916.

Application filed May 9, 1912. Serial No. 696,720.

To all whom it may concern:

Be it known that I, HENNING FRIEDRICH WALLMANN, a citizen of the United States of America, residing at Chicago, in the county of Cook and State of Illinois, have invented a new, useful, and Improved Apparatus for Distilling Fuel, of which the following is a description, reference being had to the accompanying drawings, forming a part of this specification, in which similar letters and numerals of reference in the several figures indicate similar parts.

My invention relates to apparatuses for distilling fuel or hydro-carbonaceous substances, such as bituminous coal, lignite, wood, peat, garbage, etc., and more particularly to apparatuses by which great quantities of hydro-carbonaceous fuel can be quickly heated in consecutive order by means of the continuous combustion of a minimum amount of fuel and can thereby be distilled and coked in consecutive order, but in a very short space of time; and the objects of my improvements are, first, to provide preferably a plurality of substantially vertical distillation conduits each with two opposite short, stationary and two opposite long, movable side-walls of which the latter preferably are parallel to each other and constructed of well heat-conducting material; second, to provide the said long movable side-walls with apertures for the passage of a distilling agent in gaseous form; third, to provide on one of two opposite long sides of each distillation conduit a movable heating chamber with one or two of said long side-walls as part or parts respectively of construction; fourth, to provide on the other of said two opposite long sides of each distillation conduit a movable chamber or discharge-canal for distillates with one or two of said long side-walls as part or parts respectively of construction; fifth, to supply a heating agent or heating agents, preferably a combustible and air into the said movable heating chamber and, in the preferred case, to burn the said combustible in the said heating chamber; sixth, to provide means for continuously conveying hydro-carbonaceous fuel in a certain direction through each of the said distillation conduits and for continuously moving a distilling agent, preferably hot gaseous products of combustion or steam or a mixture of such fluids through the conveyed fuel in a direction transverse to the direction of

the fuel conveyance toward the said movable chamber or chambers for distillates; seventh, to divide the said chamber for distillates into several compartments for separating from each other distillates generated at different stages of distillation; eighth, to support each of the said movable chambers by means of rollers and to provide suitable mechanical means for moving and preferably for reciprocating the said chambers, preferably in opposite directions, with respect to each other; ninth, to provide special suitable means for producing a heating and distilling agent; tenth, to provide means for simultaneously cooling and discharging the residue of distillation, in special cases, the produced coke or charcoal and for properly utilizing the heat withdrawn from such residue; and eleventh, to cool a first portion of distillates generated from moist fuel to thereby condense steam of said portion, to discharge separately from each other the resulting water and a non-condensed part of the said portion, and to lead this non-condensed part into incandescent residue of distillation. I attain these objects by the apparatus illustrated in the accompanying drawings, in which—

Figure 1 is a vertical section through one special form of the apparatus; Fig. 2 is a vertical section at right angles to Fig. 1 and on the dotted line *m—m* in Fig. 1; Fig. 3 is a horizontal section on the line *n—n* in Figs. 1 and 2; Figs. 4 and 5 illustrate a detail of construction; Fig. 6 illustrates a detail of the improved apparatus.

R is a receptacle or hopper for solid fuel located above a plurality of distillation conduits *D*, *D*. A screw-conveyer *S* may be provided for transporting fuel from a magazine *M* into the receptacle *R*, and a link-belt conveyer *L* may evenly distribute the fuel into the distillation conduits *D*, *D*. Each of the latter is oblong in plan, and on one of its long sides is located a heating vessel *H* and on the opposite side a vessel *C* for distillates. The heating vessels *H*, *H* as well as the vessels *C*, *C* for distillates are each movably supported by rollers, balls or wheels *10*, *10* located and properly supported within chambers *B*, *B* separated by means of partitions *11*, *11* from the distillation conduits *D*, *D* and by means of partitions *12*, *12* from each other. Such movable heating vessels or vessels for distillates as are exposed to a one-sided pressure may

be sidewise supported by side rollers or balls 13, 13. Any suitable mechanical means may be used for reciprocating the vessels H, H and C, C in opposite horizontal directions and preferably so that two neighboring vessels move always in opposite directions with respect to each other. In the drawings is indicated a crank shaft 14 with cranks 15 properly connected to the heating vessels H, H and with cranks 16 at an angle of 180 degrees relative to the cranks 15 for reciprocating the vessels C, C for distillates.

The movable vessels H and C extending into the chambers B, B pass through suitable openings in the partition 11 which openings may fit well enough to prevent an entrance of a considerable amount of solid fuel from the distillation conduits D, D into the chambers B, B or special means may be provided for preventing such an entrance. In Figs. 3, 4 and 5 two movable plates 17, 17 with tapered edges are indicated which may be adjustably pressed against the sides of the movable vessels H and C by means of cams 18. Any solid fuel that notwithstanding enters into the chambers B, B may be removed through ports 19.

Any suitable heating agent, preferably hot combustible gas may be supplied into the lower part of each heating vessel H and may pass through conduits 20, 20, a distributing canal 21 and through gas outlets 22 into a heating chamber 23, and in the case that it is intended to burn the gas, air may also be introduced into said heating chamber 23 by means of the pipe and regulating valve 24, the air chamber 25 and the air-outlets 26. The gas may be ignited by spontaneous ignition, if hot enough, or by any suitable means, eventually through the ports 27 and 28. The resulting products of combustion may be discharged from each heating vessel H through the pipe and valve 29 into a chimney and the atmosphere, or the heating agent, whatever it may consist of, may be delivered through conduits 30 and 31 and horizontal slots 32 and 33 into the fuel contained in the appertaining distillation conduit D for heating and distilling the fuel therein. Said conduits 30 and 31 are oblong in their cross section and establish two rows of slots, said rows extending past the whole length or past the greater part of the length of the appertaining conduit D with the combined lengths of said slots longer than half the length of said conduit. The resulting mixture of distillates and heating and distilling agent may be sucked by means of exhausters E¹ and E² and suitable pipe connections into the horizontal slots 36 and 37 respectively and into the interior of the vessels C, C for distillates.

In the case that moist fuel such as peat, moist lignite or garbage is distilled, the dis-

tillates generated in the upper part of the distillation conduits D, D and containing much steam may be kept separate from the rest of the distillates generated farther down in the distillation-conduits D, D, in order that distillates of different chemical character may later be treated and utilized or destroyed in a different way. For this purpose a partition 38 may be provided in each vessel C and also a body of non-conducting material 39 preventing an exchange of temperature between distillates of different chemical character. In the case that the distillates first generated from moist fuel contain some valuable noncondensable gas or some disease producing germs from garbage, the combined exhauster and blower E¹ may suck such distillates from the slots 36 and the pipe 74 through a condenser W¹ (Fig. 6) for condensing steam, etc., for eventually discharging the resulting water past an S shaped pipe or trap into a sewer and for delivering the non-condensable gas to any desirable location, preferably into a body of incandescent fuel, especially in the case that the non-condensable gas contains disease producing germs from garbage.

In order to produce a heating and distilling agent, I preferably gasify a part of the residue of distillation and for this purpose I preferably arrange a combustion-chamber or producer-shaft P below the distillation conduits D, D, as shown in Figs. 1 and 2.

The fuel in the producer-shaft P in Figs. 1 and 2 is supported by means of a chain or link-belt-conveyer F and by means of cooling vessels K, K¹, movably supported by rollers, balls or wheels 10^a located and supported in turn within chambers B¹, B¹ separated by means of partitions 11^a, 11^a from fuel conduits G, G below the producer-shaft P. A crank shaft 14^a with cranks 15^a and 16^a arranged at angles of 180 degrees with respect to each other, may reciprocate the vessels K and K¹ preferably in horizontal directions, but in opposite directions with respect to each other. Air and preferably water or steam is supplied through pipes 40 into the vessels K and K¹ for absorbing heat from the residue of distillation before the discharge thereof from the lower part of the apparatus by means of the conveyer F. The resulting hot mixture of air and steam leaves the vessels K and K¹ through horizontal slots 34 and after entering into the lower part of the producer-shaft P rises in the fuel bed therein toward the lower end of canals 35 and 35 of the vessels C, thereby generating semi-water gas in the well known way. These canals 35 are provided in stationary walls of refractory material 41, each such wall being suspended below a reciprocally mov-

able vessel H by means of a stationary metal frame 42 preferably consisting of two long pieces of cast iron bolted together with the top of a refractory wall between them. 5 These stationary walls 41 extend down into the fuel-bed within the producer shaft P and the canals 35 communicate through conduits 20, gas distributing canals 21 and gas outlets 22 with heating chambers 23 so that 10 gas generated in the producer shaft P may flow into the heating chambers 23 and may preferably be consumed therein.

Each of the vessels C being divided by partitions into several compartments, the 15 lowest 43 of the latter is open at its bottom and is connected by means of a pipe 44 to an exhauster E³ for sucking a part of the semi-watergas generated in the producer shaft P, through fuel located above the lower end of 20 the walls 41 and below that of the vessels C. The hot semi-watergas in flowing from the producer shaft P toward the chambers 43 acts as a distilling agent on this fuel and evaporates the rest of volatile matter contained 25 therein.

The movable parts of the required piping as are connected to the movable vessels H, C, K, K¹ are operatively connected to stationary pipes, exhausters or other stationary 30 parts of the apparatus by means of stuffing boxes 45 or by similar devices as will be understood by any mechanic.

The movable vessels H and C may preferably be provided with studs 4 for crushing 35 the fuel before it drops from the distillation conduits D, D into the producer-shaft P.

As the flow of the fluid in this apparatus is promoted preferably by suction, proper 40 care is taken that air from the atmosphere can enter into the apparatus only at desirable places and not through a magazine M or through a store-room into which the produced coke is delivered by means of the conveyer F.

The products of combustion resulting 50 from the burning of semi-watergas in the heating-chambers 23 consist mainly of nitrogen, carbonic acid gas and steam, forming a mixture which by its passage through the fuel between the slots 33 and 37 at a moderate temperature not effecting a reduction of the carbonic acid gas to carbon-monoxid, mixes with permanently gaseous and also with condensable distillates such as tar, naphtha, ammonia, etc. I heat the mixture of same and distilling fluid to red heat, thus decomposing the condensable distillates and disengaging carbon therefrom which in its 55 nascent state combines with the carbonic acid to carbon-monoxid, the result being that the condensable distillates are converted into a permanent, fixed gas without a consequential amount of solid or condensable residue remaining therefrom. This result

may be obtained by leading the mixture of distillates and distilling fluid through a body of incandescent solid fuel (coke), as will be understood by every engineer. In larger gas plants where it is of advantage 70 to separately utilize the condensable distillates or a part thereof, I separate the same from the permanently gaseous part of the gas mixture by the same means that are ordinarily used for the same or a similar 75 purpose.

The apparatus operates as follows: After some easily burning fuel has been placed on the conveyer F, being at rest, and has been ignited in any suitable way with the valves 80 29 open to a chimney, more fuel may be supplied into the chambers G, G, and into the producer-shaft P and some air, water or steam may be admitted into the vessels K and K¹ where the water will evaporate with increased heat from the fire. The exhausters E¹, E² and E³ may then be started and more fuel supplied until the producer-shaft P and the distillation conduits D, D are filled with fuel to their top. As soon as the 90 fuel in the producer-shaft P has become incandescent, semi-watergas will be generated and flow into the heating chambers H, H where it can be ignited through ports 27 and 28 after air has been admitted through the 95 valves and pipes 24. A slow rotation of the crankshafts 14 and 14^a may now be started and thereby a reciprocal motion of the vessels H, C, K and K¹ for agitating the fuel in the conduits D and G. By now 100 closing the valves 29, the exhausters E¹ and E² suck products of combustion from the heating chambers 23 through the fuel in the conduits D, D and eventually through the condenser W¹ and deliver each a mixture 105 of products of combustion and uncondensed distillates to some predetermined location. The exhauster E³ sucks at the same time semi-watergas through the fuel in the upper part of the producer-shaft P, thereby 110 completely evaporating all volatile ingredients of this fuel. As soon as the process of distillation is thus sufficiently advanced, the conveyer F may start to deliver the residue 115 of distillation into a store-room separated from the atmosphere.

In the case that it is not intended to manufacture coke or charcoal, the cooling chambers K and K¹ and the conveyer F may be dispensed with and a suitable grate substituted.

With the use of certain kinds of fuel a crushing of the produced coke or charcoal may not be necessary and the studs 4 may accordingly be dispensed with. Also the 120 conveyer F may be provided with means for breaking the produced coke or charcoal when discharged from the lower end of the conduits D, D, and, with such provision made, the studs 4 may be dispensed with. 125

In such case the stroke of the reciprocal motion of the vessels C¹ and H¹ may be reduced to a few inches or to an inch.

In the case that the production of a gas not containing a substantial quantity of free nitrogen is desired, the slots 32 and 33 may be dispensed with and the products of combustion may be discharged from the heating vessel 23 through a pipe 29 (Figs. 1 and 2).

In order to more effectively heat the fuel in the distillation conduits D, D by means of a heating vessel not in communication therewith but heated to a higher temperature, a part of the heating vessel, especially a part of its long sidewalls may be made of refractory material such as porcelain, etc.

In the case that it is desirable for reasons explained above to lead non-condensable gas from moist fuel and from a condenser W¹ into incandescent residue of distillation or into a gas flame, an exhauster E¹ may be connected either to a pipe 40 and thereby to a cooling vessel K or K¹.

25 I claim:

1. In an apparatus for fractionally distilling solid fuel, a distillation conduit constructed to convey solid fuel from a locality of lower toward one of higher temperature, means for heating fuel conveyed within said conduit, an inlet for fuel and an outlet for solid combustible into and out of respectively said conduit, a plurality of outlets for distillates from said conduit and intermediate between said inlet and said outlet at localities of temperatures different from each other, and a plurality of canals each communicating through one of said outlets for distillates with said conduit, and said canals adapted to keep apart distillates of different chemical character.

2. In an apparatus for distilling fuel, a distillation conduit, a movably supported heating vessel adapted to transfer heat to solid fuel in said conduit, a movably supported vessel for the discharge of distillates from the said conduit, and mechanical means for moving the two said vessels for agitating fuel in said conduit.

3. In an apparatus for distilling fuel, a distillation conduit, two movable side-walls of the said conduit on opposite sides thereof, means for transferring heat to solid fuel in said conduit, a canal for the discharge of distillates from the said conduit, and mechanical means for moving said two sidewalls and for thereby agitating fuel in said conduit.

4. In an apparatus for distilling fuel, a distillation conduit, a movably supported heating vessel adapted to transfer heat to fuel in said conduit, a combustion chamber within said vessel, means for supplying fuel and air into said combustion chamber, and mechanical means adapted to be continu-

ously in operation for moving said vessel and for thereby agitating fuel in said conduit.

5. In an apparatus for distilling fuel, a distillation conduit for distilling fuel, two stationary side-walls of the said conduit on opposite sides thereof, two movable side-walls of the said conduit on opposite sides thereof, and mechanical means adapted to move the said two movable side-walls for thereby agitating fuel in said conduit.

6. In an apparatus for distilling fuel, a distillation conduit, two perforated movable side-walls on opposite sides of said conduit, a canal for supplying a gaseous distilling fluid through one of said sidewalls into said conduit, and a second canal for discharging a mixture of distillates and gaseous distilling fluid from said conduit through the other of said sidewalls.

7. In an apparatus for distilling fuel, a plurality of oblong, substantially parallel distillation conduits, two stationary sidewalls on opposite sides of each of the said conduits, two movable sidewalls on opposite sides of each of the said conduits, and mechanical means for moving said movable sidewalls.

8. In an apparatus for distilling fuel, a plurality of oblong substantially parallel distillation conduits, two perforated sidewalls on opposite sides of and in contact with the fuel within each of said conduits, a source of hot distilling fluid, and two canals provided for each of said conduits, 100 one of said two canals communicating with said source and through one of said two perforated walls with the appertaining conduit, and the other of said two canals communicating through the other of said two 105 perforated walls with the same conduit for discharging therefrom a mixture of distillates and said fluid.

9. In an apparatus for fractionally distilling solid fuel, a distillation conduit constructed to convey solid fuel from a locality of lower toward one of higher temperature, means for heating fuel conveyed within said conduit, three outlets for distillates from said conduit at localities of temperatures 115 different from each other, and means for keeping apart distillates of different chemical character.

10. In an apparatus for fractionally distilling solid fuel, a distillation conduit constructed to convey solid fuel from a locality of lower toward one of higher temperature, a plurality of inlets for distilling fluid and a plurality of outlets for mixtures of said fluid and of distillates into and out of respectively said conduit at localities of temperatures different from each other, and a plurality of canals for discharging from said outlets separately from each other distillates of different chemical character.

11. In an apparatus for fractionally distilling solid fuel, a distillation conduit constructed to convey solid fuel in downward direction from a locality of lower toward one of higher temperature, means for heating fuel conveyed within said conduit, means for agitating fuel in substantially horizontal directions within said conduit, and a plurality of outlets for distillates from said conduit at localities of temperatures different from each other: 5
12. In an apparatus for continuously distilling fuel, a distillation conduit constructed to continuously convey fuel from an inlet for fuel in substantially vertical direction toward an outlet for solid combustible, means provided to be continuously in operation for supplying fuel into said inlet and for discharging solid combustible from said outlet, a combustion chamber lateral to said conduit and constructed to produce, while in operation, always gaseous products of substantially, continually uniform chemical character, means for moving hot gaseous products of combustion from said chamber through fuel conveyed within said conduit, and means for separating resulting gaseous mixture of said products and of distillates from resulting residue of distillation. 15
13. In an apparatus for distilling fuel, a substantially vertical distillation conduit, an inlet for fuel at the upper and an outlet for solid combustible at the lower end of said conduit, a continual source of combustible gas of substantially, continually uniform chemical character, a combustion chamber lateral to said conduit, an inlet for combustible gas from said source and an air-inlet into said chamber, and means for moving hot gaseous products of combustion from said chamber through fuel within said conduit. 20
14. In an apparatus for continuously distilling fuel, a distillation conduit constructed to continuously convey fuel from an inlet for fuel toward an outlet for solid combustible, means for continuously supplying fuel into said inlet and for continuously discharging solid combustible from said outlet, a continual source of combustible gas of substantially, continually uniform chemical character, a heating chamber lateral to said conduit and communicating with said source and constructed to heat fuel conveyed within said conduit, and an inlet for a hot distilling fluid not containing a consequential amount of free oxygen into, and an outlet for mixture of said fluid and of distillates out of said conduit through sidewalls thereof and at localities intermediate between said inlet for fuel and said outlet for solid combustible. 25
15. In an apparatus for continuously and fractionally distilling fuel, a distillation conduit constructed to continuously convey fuel from a locality of lower toward one of higher temperature and to fractionally distil said fuel during its conveyance, a plurality of inlets and a plurality of outlets through sidewalls of said conduit and at localities of temperatures different from each other, a combustion chamber communicating through said inlets with said conduit and provided for delivering gaseous products of combustion thereinto, and a plurality of canals each communicating through one of said outlets with said conduit and provided for keeping apart distillates of different chemical character. 30
16. In an apparatus for fractionally distilling fuel, a distillation conduit constructed to convey fuel from a locality of lower toward one of higher temperature and to fractionally distil said fuel, an inlet for fuel into and an outlet for solid combustible out of said conduit, a heating chamber lateral to said conduit, an inlet and an outlet for a heating fluid into and out of respectively said chamber, a wall qualified to transfer heat from contents of said chamber to fuel conveyed within said conduit, and a plurality of outlets for distillates from said conduit intermediate between said inlet for fuel and said outlet for solid combustible and at localities of temperatures different from each other for discharging separately from each other distillates of different chemical character. 35
17. In an apparatus for distilling fuel, a distillation conduit with two opposite short and two opposite long sidewalls in its horizontal cross-section, an inlet for fuel and an outlet for solid combustible at the upper and lower end respectively of said conduit, a substantially horizontal slot for the passage of fluid provided in one of the said long sidewalls at a locality intermediate between said inlet and the said outlet, said slot extending past the whole length or past the greater part of the length of said long sidewall, and means for moving fluid through said slot. 40
18. In an apparatus for distilling fuel, a distillation conduit with two opposite short and two opposite long sidewalls in its horizontal cross-section, an inlet for fuel and an outlet for solid combustible at the upper and lower end respectively of said conduit, a substantially horizontal row of slots for the passage of fluid provided in each of the said long sidewalls at a locality intermediate between said inlet and said outlet, said row extending past the whole length or the greater part of the length of said long sidewall and the combined length of said slots occupying more than one half of said length of sidewall, and means for moving fluid through said slots. 45
19. In an apparatus for distilling fuel, a distillation conduit, means for heating fuel 50

- within said conduit, a cooling vessel, an inlet for a cooling agent into said vessel, a heat-conducting wall of said vessel and constructed to be in contact on one side, with 5 said agent and on an opposite side with hot combustible residue of distillation, and a conveyer below said vessel and constructed to convey combustible residue of distillation discharged from said conduit.
- 10 20. In an apparatus for distilling fuel, a distillation conduit, means for heating fuel within said conduit, a movable cooling vessel, means for moving said vessel, an inlet for a cooling agent into said vessel, and a 15 heat-conducting wall of said vessel and constructed to be in contact on one side with said agent and on an opposite side with hot combustible residue of distillation for cooling this residue.
- 20 21. In an apparatus for distilling fuel, a distillation conduit, means for heating fuel within said conduit, a reciprocally movable cooling vessel, means for reciprocating said vessel, an inlet for a cooling fluid into said 25 vessel, and a heat-conducting wall of said vessel and constructed to be in contact on one side with said fluid and on an opposite side with hot, combustible residue of distillation for cooling this residue.
- 30 22. In an apparatus for distilling fuel, a distillation conduit, a heating chamber, an inlet for a heating agent into said chamber, a heat-conducting wall of said chamber constructed to be in contact on one side with 35 said heating agent and on an opposite side with fuel within said conduit, a cooling vessel, an inlet for a cooling agent into said vessel, and a heat-conducting wall of said vessel and constructed to be in contact on one 40 side with said cooling agent and on an opposite side with hot combustible residue of distillation discharged from said conduit.
- 45 23. In an apparatus for distilling fuel, a distillation conduit, a heating chamber lateral to said conduit and communicating therewith, an inlet for a heating fluid not containing a consequential amount of free oxygen into said chamber, a canal for the discharge of distillates and lateral to said 50 conduit but on an opposite side thereof with respect to said chamber, and means for sucking said fluid into said chamber and for sucking distillates from said conduit into and out of said canal.
- 55 24. In an apparatus for distilling fuel, a distillation conduit, a combustion chamber for heating fuel within said conduit and lateral to the latter, an inlet for combustible and an air-inlet into said chamber, a plurality 60 of canals separate from each other for the discharge of distillates and lateral to said conduit but on an opposite side thereof with respect to said chamber, and means for sucking distillates from said conduit into each of said canals and to discharge distil- 65
- lates from each of the same separately and kept apart from distillates sucked into and discharged from any other of said canals.
25. In an apparatus for distilling fuel, two distillation conduits, an inlet and an outlet for solid fuel into and out of respectively each of said two conduits, a combustion chamber between the two said conduits and constructed to heat fuel within each of the latter, two inner walls each between said chamber and one of said two conduits, two outer walls each at the opposite side of one of said two conduits with respect to the pertaining inner wall, and each said outer wall provided with an outlet for distillates. 70
26. In an apparatus for distilling fuel, a plurality of distillation conduits substantially parallel to each other and each oblong in a horizontal cross-section thereof, an inlet for solid fuel into the upper part and an outlet for combustible residue of distillation from the lower part of each of said conduits, a plurality of heating chambers each adjacent to one of said conduits and located on a first oblong side thereof, a plurality of discharge-chambers adjacent to but kept apart from each other for the separate discharge of distillates of different character from each one of said conduits and located on an opposite oblong side of each one of 90 said conduits with respect to said first oblong side, and a wall constructed to keep apart the contents of each two of said adjacent discharge chambers. 95
27. In an apparatus for distilling fuel, a plurality of distillation conduits each constructed to convey solid fuel in a substantially vertical direction and to distil said fuel during its conveyance, a plurality of combustion chambers each lateral to one of 100 said conduits and each constructed to heat fuel in one of the latter, a conveyer constructed to deliver combustible residue of distillation discharged from the lower part of each one of said conduits, a mechanism 105 constructed to deliver fuel into the upper part of each one of said conduits, and means for moving said conveyer and said mechanism. 110
28. In an apparatus for distilling fuel, a plurality of distillation-conduits, an inlet for solid fuel into and an outlet for residue of distillation out of each one of said conduits, a plurality of heating chambers each lateral to and communicating with one of 115 said conduits, an inlet for a distilling fluid into each one of said heating chambers, a plurality of discharge chambers each lateral to and communicating with one of said conduits, and means for leading said fluid into and through said heating chambers, into and through said conduits and into and through said discharge-chambers for heating fuel within said conduits and for dis- 120
- charging resulting distillates. 125
- 130

29. In an apparatus for distilling fuel, a plurality of substantially upright distillation conduits lateral and substantially parallel to each other and each oblong in a horizontal cross-section thereof, an inlet for solid fuel into the upper part and an outlet for combustible residue of distillation from the lower part of each of said conduits, a plurality of combustion chambers each oblong in a horizontal cross-section thereof and each adjacent and lateral to and between two of said conduits, an inlet for combustible and an air-inlet into and an outlet for gaseous products of combustion out of each of said chambers, and means for transferring heat from said gaseous products to solid fuel within said conduits.
30. In an apparatus for distilling fuel, two substantially upright distillation conduits lateral and substantially parallel to each other and each oblong in a horizontal cross-section thereof, an inlet for solid fuel into the upper part and an outlet for residue of distillation from the lower part of each of said conduits, two heating chambers each lateral and substantially parallel to one of said conduits and communicating therewith and oblong in the same said cross-section, a source of heating agent communicating with each of said heating chambers, a discharge chamber lateral and substantially parallel to and between said conduits and communicating therewith and oblong in the same said cross-section, and means for leading gaseous fluid from said source through said heating chambers and through said conduits into and through said discharge chamber.
31. In an apparatus for distilling fuel, two combustion chambers, an inlet for combustible and an air-inlet into each one of said two chambers, a distillation conduit between the said two chambers, a wall between each one of said chambers and said conduit, an inlet for solid fuel into the upper part of said conduit, an outlet for combustible residue of distillation from the lower part of said conduit, and means for leading hot gaseous products from one of said chambers through fuel in said conduit.
32. In an apparatus for distilling fuel, a conduit constructed to convey and distil fuel, an inlet for fuel into and an outlet for combustible residue of distillation from said conduit, a combustion chamber lateral to said conduit, a wall between said chamber and said conduit, an inlet for combustible and an air-inlet into said chamber, and means for leading hot gaseous products of combustion from said chamber past said wall through fuel within said conduit.
33. In an apparatus for distilling fuel, a conduit oblong in a horizontal cross-section and constructed to convey and to distil solid fuel, two opposite long and two opposite short side walls of said conduit, an inlet for solid fuel into the upper part of said conduit, an outlet for residue of distillation from a lower part of said conduit, means for heating one of said long side walls, an aperture in the other of said long side-walls, and a canal communicating through said aperture with said conduit for discharging generated distillates.
34. In an apparatus for distilling fuel, a conduit oblong in a horizontal cross-section and constructed to convey and to distil solid fuel, two opposite long perforated and two opposite short sidewalls of said conduit, means for heating a first of said long perforated walls, means for leading a hot gaseous distilling fluid through said first of said long perforated walls into and through fuel within said conduit, an outlet for a mixture of said fluid and distillates from the upper part of said conduit, and a canal communicating through a second of said long perforated walls with said conduit for discharging distillates therefrom.
35. In an apparatus for distilling fuel, two separate combustion chambers at a distance from each other, a separate inlet for combustible and a separate air-inlet into each one of said two chambers, means for conveying solid fuel heated in a location between said two chambers toward an outlet for residue of distillation, means for leading hot gaseous products of combustion from said two chambers into and through said solid fuel during said conveying, and means for discharging separately from each other combustible residue of distillation and a mixture of distillates and of said products.
36. In an apparatus for distilling fuel, a distillation conduit oblong in a horizontal cross-section thereof and provided with two opposite long and two opposite shorter sidewalls and constructed to convey fuel from an inlet for fuel toward an outlet for solid combustible with said fuel distilled during its conveyance, means for heating one of said two long sidewalls and thereby fuel conveyed in said conduit, a mechanical member provided to be in operation for the impeding of an adherence of fuel under distillation within said conduit, to said one of said long sidewalls, and means for moving said member.
37. In an apparatus for distilling fuel, a distillation conduit oblong in a horizontal cross-section thereof and provided with two opposite longer and two opposite shorter side walls and constructed to convey fuel from an inlet for fuel in downward direction toward an outlet for solid combustible with said fuel distilled during its conveyance, means for heating fuel within said conduit, and means for agitating fuel

adjacent to said longer walls in substantially horizontal directions for impeding its adherence to said longer walls.

38. In an apparatus for distilling fuel, 5 a plurality of distillation conduits each oblong and all to each other substantially parallel in a horizontal cross-section and constructed to convey fuel from an inlet for fuel toward an outlet for solid combustible with said fuel distilled during its conveyance, a mechanical member provided for each one of said conduits to impede an adherence of fuel to a wall of the appertaining conduit, and means for moving said member.

39. In an apparatus for continuously and fractionally distilling fuel, a distillation conduit constructed to continuously convey a mass of fuel from a locality of lower toward one of higher temperature and to fractionally distil said mass during its conveyance, means for heating said mass, means for withdrawing distillates from said mass, and means for keeping apart from each other distillates evaporated at localities of temperatures different from each other.

40. In an apparatus for continuously and fractionally distilling fuel, a plurality of distillation conduits each constructed to convey a mass of fuel from a locality of lower toward one of higher temperature and to fractionally distil said mass during its conveyance, means for withdrawing distillates from said mass, and means for keeping apart from each other distillates evaporated at localities of temperatures different from each other.

41. In an apparatus for distilling fuel, a plurality of distillation conduits each oblong in a horizontal cross-section and each constructed to convey fuel from an inlet for fuel toward an outlet for solid combustible with said fuel distilled during its conveyance, two opposite shorter and two opposite longer sidewalls provided for each of said conduits, and a plurality of substantially horizontal slots provided in each of said longer walls for the passage of fluid and located between said inlet and said outlet and means for moving fluid through said slots.

42. In an apparatus for continuously distilling fuel, a distillation conduit constructed to continuously convey fuel from an inlet for fuel toward an outlet for solid combustible with said fuel distilled during its conveyance, a conveyer constructed to be continuously in operation for supplying fuel toward said inlet, a second conveyer constructed to be continuously in operation for delivering solid combustible discharged from said outlet, means for heating fuel conveyed in said conduit, and means for continuously separating resulting distillates from resulting combustible residue of distillation.

43. In an apparatus for distilling fuel, a plurality of distillation conduits each oblong and all to each other substantially parallel in a horizontal cross-section thereof and each constructed to convey fuel from an inlet for fuel toward an outlet for solid combustible with said fuel distilled during its conveyance, two opposite shorter and two opposite longer sidewalls provided for each of said conduits, and a plurality of substantially horizontal rows of slots provided in each of said longer walls for the passage of fluid and located between said inlet and said outlet and each row extending past the whole length or the greater part of the length of the appertaining conduit, and means for moving fluid through a part of said slots into and through another part of said slots out of the appertaining conduit.

44. In an apparatus for distilling fuel, a distillation chamber, means for supplying solid fuel into and for discharging solid combustible out of said chamber, means for heating and for thereby distilling fuel within said chamber, means for separating resulting distillates from resulting residue of distillation, means for preventing an entrance of a consequential amount of air of natural chemical character into said chamber, a source of carbonic acid, a canal constructed to be free of a consequential amount of solid fuel, and means for supplying carbonic acid from said source through said canal into said residue within said distillation chamber after said distillates have been separated from said residue.

45. In an apparatus for distilling fuel, a distillation chamber, means for supplying solid fuel into and for discharging solid combustible out of said chamber, means for heating and for thereby distilling fuel within said chamber, means for separating resulting distillates from resulting residue of distillation, means for preventing an entrance of a consequential amount of air of natural chemical character into said chamber, a combustion chamber constructed to produce, while in operation, always gaseous products not containing a consequential amount of free oxygen but containing a substantial amount of carbonic acid as result of almost complete combustion, means provided to prevent an entrance of a consequential amount of solid fuel from said distillation chamber into said combustion chamber, means for supplying gaseous products from the latter said chamber into residue previously separated from said distillates, and means for discharging resulting gaseous fluid from said residue.

46. In an apparatus for distilling fuel, a distillation chamber, means for supplying solid fuel into and for discharging solid combustible out of said chamber, means for heating and for thereby distilling fuel

- within said chamber, means for separating resulting distillates from resulting residue of distillation, means for preventing an entrance of a consequential amount of air of natural chemical character into said chamber, a continual source of combustible gas of substantially continually, uniform chemical character, an air supply, a combustion chamber communicating with said source, 5 with said air supply and with said distillation chamber, means provided to prevent an entrance of a consequential amount of solid fuel from said distillation chamber into said combustion chamber, means for 10 supplying gaseous products of combustion from the latterly said chamber into residue previously separated from said distillates, and means for discharging resulting fluid from said residue. 15
- 20 47. In an apparatus for distilling fuel, a distillation chamber, means for supplying solid fuel into and for discharging solid combustible out of said chamber, means for heating and for thereby distilling fuel within said chamber, means for separating resulting distillates from resulting residue of distillation, means for preventing an entrance of a consequential amount of air of natural chemical character into said chamber, a primary combustion chamber constructed to produce, while in operation, always substantially one and the same kind of combustible gas with respect to the chemical character 25 thereof, an air-supply, a secondary combustion chamber in communication with said primary combustion chamber, with said air-supply and with said distillation chamber and constructed to produce gaseous products containing a substantial amount of carbonic acid, and means for supplying resulting gaseous products from said secondary combustion chamber into residue separated from said distillates. 30
- 45 48. In an apparatus for fractionally distilling fuel, a distillation conduit constructed to convey a mass of solid fuel from a zone of lower temperature in consecutive order through a plurality of distillation zones of gradually increased temperatures—each subsequent zone of a higher temperature than the preceding zone—toward a receptacle for solid combustible, means for preventing an entrance of a consequential amount of free oxygen from the atmosphere into fuel conveyed within said zones, means for heating fuel conveyed within said distillation zones, means for agitating fuel within said distillation zones 50 in directions transverse to the direction of its conveyance, and means for discharging generated distillates separately out of each one of said distillation zones. 55
- 60 49. In an apparatus for distilling fuel, a distillation conduit constructed to convey fuel from an inlet for fuel toward an outlet for combustible residue of distillation, means for heating and thereby distilling fuel conveyed within said conduit, a movable sidewall of said conduit and located between said inlet and said outlet, and means for moving said sidewall. 65
- 70 50. In an apparatus for distilling fuel, a distillation conduit constructed to convey fuel from an inlet for fuel toward a cooling conduit, means for heating and thereby distilling fuel within said distillation conduit, means for cooling combustible residue of distillation within said cooling conduit, a movable wall of said cooling conduit, and means for moving said wall. 75
- 80 51. In an apparatus for distilling fuel, a distillation conduit constructed to convey fuel from an inlet for fuel toward an outlet for combustible residue of distillation, an aperture in a sidewall of said conduit and located between said inlet and said outlet, means provided to prevent an entrance of a consequential amount of air in its natural chemical composition into said conduit, a combustion chamber communicating through said aperture with said conduit and constructed to produce, while in operation, always gaseous products of substantially, continually uniform chemical character, and means for discharging a mixture of said gaseous products and of distillates from said conduit. 85
- 90 52. A combination with an apparatus for fractional distillation and comprising, a plurality of distillation-zones partly of lower and partly of higher temperature with respect to each other, a receptacle for combustible residue of distillation, a conduit, means for moving portions of a mass of solid fuel in downward direction within said conduit through said zones toward said receptacle, means for preventing an entrance of a consequential amount of air of natural chemical character into said conduit, a heating chamber lateral to said conduit and adapted to heat fuel in the latter, a plurality of separate receptacles for distillates of different chemical character and located at the exterior of but in operative proximity to said apparatus, and a plurality of canals each constructed to deliver separately from any other of said canals distillates from one of said zones to one of said receptacles for distillates. 95
- 100 53. A combination with an apparatus for fractional distillation and comprising, a plurality of distillation zones partly of lower and partly of higher temperature with respect to each other, a conveyer for delivering combustible residue of distillation, a conduit, means for moving portions of a mass of solid fuel within said conduit through said zones toward said conveyer, a plurality of separate receptacles for dis- 105
- 110 115
- 120 125
- 130

- tillates of different chemical character and located exterior of but in operative proximity to said apparatus, and a plurality of canals each constructed to deliver separately from any other of said canals distillates from one of said zones to one of said receptacles for distillates.
54. A combination with an apparatus for fractional distillation and comprising, a 10 first distillation zone of lower and a second distillation zone of higher temperature with respect to each other, a receptacle for combustible residue of distillation, a conduit, means for moving portions of a mass of 15 solid fuel within said conduit through said zones toward said receptacle, means for preventing an entrance of a consequential amount of air of natural chemical character into said conduit, an aperture in a sidewall 20 of said conduit, means for heating and for thereby distilling fuel in said first zone, means for leading a distilling fluid containing a substantial amount of carbonic acid through said aperture into fuel within said 25 second zone, two separate receptacles for distillates of different chemical character and located exterior of but in operative proximity to said apparatus, and two canals each constructed to deliver separately from 30 the other one thereof distillates from one of said zones to one of said receptacles for distillates.
55. In an apparatus for distilling fuel, two walls at a distance from each other, 35 two apertures one thereof provided within one and the other thereof provided within the other of said walls, a receptacle for solid fuel, means for moving a mass of fuel between and in contact with said walls 40 from said receptacle past said apertures toward an outlet for combustible residue of distillation, means for leading through each one of said apertures gaseous products of combustion not containing a consequential amount of air of natural chemical character, into fuel between said walls, and means for separating resulting fluid from resulting combustible residue of distillation.
56. In an apparatus for the production 50 of distillates and combustible residue of distillation, a distillation conduit, means for moving a mass of solid fuel from a receptacle therefor in downward direction through said conduit toward an outlet of 55 the latter, means for leading a hot distilling fluid not containing a consequential amount of air of natural chemical character, into fuel of said mass while moving within said conduit, means for separating resulting mixture of said fluid and distillates from resulting combustible residue of distillation, and means for transporting resulting separated combustible residue from below said outlet in a direction transverse to the direc- 60 tion of said moving toward the exterior of said apparatus.
57. A combination with an apparatus for fractional distillation and comprising, a receptacle for combustible residue of distillation, a distillation conduit for conveying solid fuel from a locality of lower through one of higher temperature toward said receptacle, means for preventing an entrance of a consequential amount of air into fuel within said conduit, means for heating fuel 75 conveyed within said conduit, a plurality of outlets for distillates from said conduit at localities of temperatures different from each other, a plurality of separate receptacles for distillates of different chemical 80 character and located at the exterior of said apparatus, and a plurality of canals each for delivering separately from any other of said canals distillates from one of said outlets to one of said receptacles for 85 distillates.
58. A combination with an apparatus for fractional distillation and comprising, a receptacle for combustible residue of distillation, a distillation conduit for conveying 90 solid fuel from a locality of lower past one of higher temperature toward said receptacle, means for heating fuel conveyed within said conduit, three outlets for distillates from said conduit at localities of 95 temperatures different from each other, three separate receptacles for distillates of different chemical character and located at the exterior of said apparatus, and three canals each for delivering separately from 100 the other two of said canals, distillates from one of said outlets to one of said receptacles for distillates.
59. In an apparatus for distilling fuel, a distillation chamber, means for supplying solid fuel into and for discharging combustible residue of distillation out of said chamber, means for leading a first distilling fluid not containing a consequential amount of air, into fuel within said chamber for 105 primarily distilling said fuel, means for separating resulting distillates from resulting residue, means for leading a second distilling fluid of chemical character different from that of said first fluid but not containing a consequential amount of air of natural chemical character, into said residue for secondarily distilling the latter, means for separating resulting mixture of gaseous fluids from resulting residue of secondary 110 distillation, and means for discharging separately from each other said mixture and said distillates from said chamber.
60. In an apparatus for distilling fuel, two combustion chambers at a distance from 120 each other and constructed to produce, while in operation, always substantially one and the same kind of gaseous products with

respect to the chemical character of the latter, and one of said chambers partly located in one with the other of said chambers partly located in the other of two geometrical vertical planes parallel to each other, a receptacle for solid fuel, means for moving a mass of fuel from said receptacle in downward direction between said planes toward an outlet for combustible residue of distillation, means for preventing an entrance of a consequential amount of air of natural chemical character into fuel of said mass during its said moving, means for leading gaseous products from both said

chambers through fuel of said mass during its said moving, means for separating resulting mixture of gaseous fluids from resulting combustible residue of distillation, and means for transporting resulting separated combustible residue from below said outlet in a direction transverse to that of said moving toward the exterior of said apparatus.
